HEN'S NEST

Helmer E. Smith, Sheldon, Iowa

Application July 3, 1950, Serial No. 171,877

5 Claims. (CL 119—48)

1

This invention relates to a hen's nest in which a large number of hens may be accommodated when laying.

An object of the invention is to provide a housing in which two compartments are formed by the novel construction of this invention, one of the compartments being the place for the laying fowls, while the other compartment is for the eggs that have been laid.

Another object of the invention is the construction of an efficient sectional cover or roof for the housing, one of which sections is preferably provided with a depending integral portion which constitutes a division in the housing, whereby a laying compartment and an egg compartment is formed in the housing.

A still further object of the invention is the construction of a hen's nest in which there is a hinged cover or roof section that is provided with means for automatically locking the said section in a closed position upon the housing of the nest.

Another object of the invention is the construction of an efficient perch structure, whereby the entrance of the hen into the housing is greatly facilitated.

Another object of the invention is the provision of an efficient detachable floor for the housing of this invention.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in rear elevation of a hen's nest constructed in accordance with the present invention.

Figure 2 is a view in side elevation.

Figure 3 is an enlarged central sectional view taken on line 3—3, Figure 4, and looking in the direction of the arrows.

Figure 4 is a transverse sectional view taken on line 4—4, Figure 2, and looking in the direction of the arrows.

Figure 5 is a sectional view taken on line 5—5, Figure 3, and looking in the direction of the arrows.

Figure 6 is an enlarged horizontal sectional view showing parts broken away taken on line 6—6, Figure 2, and looking in the direction of the arrows.

Referring to the drawings, in which the preferred embodiment of this invention is illustrated,

2

1 designates the housing which is open at its rear. The housing 1 is preferably provided with two brackets 2, provided with apertures 3, for suspending the nest in a building, as the operator desires.

The inclined roof or cover 4 of the housing 1 comprises a fixed section 5, a primary hinged section 6 and an auxiliary hinged section 7, Fig. 3. The sections 6 and 7 are provided with hinges 8 10 that secure the sections together. The primary section 6 is provided with an integral, depending portion 9 which normally engages angle guides 10; these guides 10 are fastened by rivets 10a to the inner faces of the sides 10b (Fig. 3) 15 of the housing, and terminate at their lower ends a distance from the detachable floor 11 sufficient to permit the eggs laid in the compartment 12 to pass into the egg-receiving compartment 13. The depending vertical portion 9 and the hinged 20 section 6 are formed of a springy sheet metal and consequently the right-angled flange 13a on the lower end of portion 9 snaps under the angle guide 10 as shown by dotted lines A in Figure 3, whereby the hinged section 6 is fastened or 25 locked on the housing in a closed position until the lower flange 13 is grasped by the operator and pulled outwardly sufficient to clear the guides 10 whereupon the hinged sections 6 and 7 may be raised for the inspection of the compartment 12. When it is desired to remove the eggs from the 30 compartment 13, it is only necessary for the operator to raise the auxiliary hinged section 7, and collect the eggs without disturbing the hens in the main compartment 12. When the eggs roll down the floor 11, passing under flange 13, they 35 will come in contact with the horizontal rubber bumper 14 without injury to the eggs.

In the sides of the housing 1 are two entrance openings 15 which allow the hens to pass into the compartment 12. On each side of the housing 40 are two vertical angle supports 16. These supports are at opposite sides of the opening 15 and on the outwardly extending portion 17 of each support is pivotally mounted at 18 a bracket 19. On a pair of these brackets 19 is a perch 20; this perch is fastened on brackets 19 by any suitable means. The inner end of bracket 19 in each instance, is cut on an inclined angle, Fig. 6, so that the brackets can be pivoted upwardly to permit the perch to be swung to a closed position 45 close to the housing when desired. When the perch is in its operating position, as shown in the drawings, the inner end 21 is impinging against the inner portion of the vertical angle support, whereby the perch is held securely in 50 55

an open horizontal position. The hen can fly to the perch 20 and easily enter the opening 15, passing thence into the compartment 12. The opening 15 is formed by cutting the metal with the portions 22, Fig. 3, turned back, whereby no sharp or cutting edges will be exposed against which hens may contact.

In the bottom of the housing 1 are preferably two slidable clean-out pans 23. The housing has horizontal flanges 24 upon which the clean-out pans 23 are mounted. Each clean-out pan 23 is provided with a grip flange 25, Fig. 3, that can be easily grasped by the operator.

The hinged auxiliary section 7 is provided with a depending grip flange 7a.

The floor 11 comprises a frame including two side sections, Fig. 6, and two end sections 27, Fig. 4. Secured to the end sections 27 are wire mesh holders 28. These wire mesh holders are each substantially U-shape in cross section. Within the wire mesh holders 28 is the wire mesh 29. The wire mesh 29, besides being secured within the holders 28, is also spot welded to the side sections 26. Each side section 26 is provided with a depending flange 30 between which flanges 30 of the two side sections 26 are positioned the tubular braces 31 and the central protecting brace 32. The central protecting brace 32 is substantially U-shape in cross section, Fig. 4, and prevents the droppings from marring or lodging upon the two central flanges 24, Fig. 4. Each tubular brace 31 is provided at its ends with right angular positioned lips 33, Fig. 6, which are preferably soldered to the flanges 30 of the side sections 26. Besides performing the function of a brace, the tubular brace 31 in each instance acts as a self-cleaning device, in that the droppings engaging the same will roll or readily drop off onto the cleaning pan 23. When it is desired to clean the nest the operator removes the floor 11 through the rear open end of the housing, and then the cleaning pans can be drawn out of the housing with the droppings and litter thereon when the cleaning of the nest is in progress.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such alterations or changes as shall fairly fall within the scope of the appended claims.

What I claim is:

1. In a hen's nest of the class described, the combination with a housing, said housing provided with guides fastened to the inner faces of its sides, a cover including a section provided with a depending portion adapted to engage said guides, and said section provided with means for engaging the bottom of said guides for locking said section in a closed position upon said housing.

2. In a hen's nest of the class described, the combination with a housing, of vertical angle guides secured to the sides of said housing, each guide terminating short of the floor of said housing, a sectional cover on said housing, said cover including a primary section and an auxiliary section, said primary section provided with an integral downwardly-extending portion engaging said guides, said downwardly-extending portion provided with a right-angled flange on its lower

edge, said right-angled flange normally positioned under the lower edges of said guides, said downwardly-extending portion producing a laying compartment and an egg compartment in said housing, said housing provided with a yieldable bumper in said egg compartment, and said auxiliary section of the cover covering said egg compartment, whereby the auxiliary section can be raised independently of the primary section.

3. In a hen's nest, a housing having parallel front and rear walls and parallel side walls extending between said front and rear walls, oppositely disposed guides secured to the inner faces of said side walls, a sectional cover supported on said side walls and including a front section fixed to the side walls and a second section hinged to the fixed section, said second section having a depending partition at its free edge, said partition normally resting against the edges of the guides confronting the rear wall, and means on the lower corners of said depending partition normally engaged beneath said guides, whereby said second section is normally prevented from opening and the partition is normally prevented from deflection by pressure at the direction of the front section.

4. In a hen's nest, a housing having parallel front and rear walls and parallel side walls extending between said front and rear walls, oppositely disposed guides secured to the inner faces of said side walls, a sectional cover supported on said side walls and including a front section fixed to the side walls and a second section hinged to the fixed section, said second section having a depending partition at its free edge, said partition normally resting against the edges of the guides confronting the rear wall, and a third cover section hinged to the second cover section at the junction of said second section and the partition.

5. In a hen's nest, a housing having parallel front and rear walls and parallel side walls extending between said front and rear walls, oppositely disposed guides secured to the inner faces of said side walls, a sectional cover supported on said side walls and including a front section fixed to the side walls and a second section hinged to the fixed section, said second section having a depending partition at its free edge, said partition normally resting against the edges of the guides confronting the rear walls, said front wall being of greater height than the rear wall and the upper edges of the side wall being inclined downwardly from the front wall to the rear wall, and lips on said second and third sections engaging over the side walls.

HELMER E. SMITH.
